[57] CLAIM

The ornamental design for a steering wheel controller, as shown and described.

DESCRIPTION

FIG. 1 is a front top, and right side perspective view of a steering wheel controller showing my new design;

FIG. 2 is a front elevational view;

FIG. 3 is a top plan view;

FIG. 4 is a right side elevational view;

FIG. 5 is a left side elevational view; and

FIG. 6 is a rear elevational view thereof.

The bottom surface is plain and unornamented with the exception of a bolt and washer assembly that is the same in appearance and placement as that seen in FIG. 3.
